UNITED STATES PATENT OFFICE.

JOSEPH PARK BABCOCK, OF TSIONAN, CHINA, ASSIGNOR TO MAH JONGG COMPANY OF CHINA, OF SHANGHAI, CHINA, A CORPORATION OF ALASKA.

DESIGN FOR A SET OF DOMINOES.

Application filed December 14, 1923. Serial No. 8,039. Term of patent 3½ years.

To all whom it may concern:

Be it known that I, JOSEPH PARK BABCOCK, a citizen of the United States, at present residing at Tsinan, China, have invented a new, original, and ornamental Design for a Set of Dominoes, of which the following is a specification, reference being had to the accompanying drawings, forming a part thereof.

Figure 1 is a plan view of a part of a set of dominoes showing my design.

Figure 2 is a plan view of the remainder of the set, and

Figure 3 is an enlarged perspective view of an individual domino.

I claim:—

The ornamental design for a set of dominoes as shown.

JOSEPH PARK BABCOCK.
